UNITED STATES PATENT OFFICE.

FREDERICK MCKEE AND CHARLES BALLINGER, OF PITTSBURG, PENNSYLVANIA, ASSIGNORS TO MCKEE AND BROTHERS, OF SAME PLACE.

GLASS-PRESSING MACHINE.

Specification forming part of Letters Patent No. 42,143, dated March 29, 1864.

To all whom it may concern:

Be it known that we, FREDERICK MCKEE and CHARLES BALLINGER, of Pittsburg, in the county of Allegheny and State of Pennsylvania, have invented certain new and useful Improvements in Steam Presses for Pressing Glass and other Vitrefied Material; and I do hereby declare that the following is a full, clear, and exact description of the same, reference being had to the accompanying drawing, making a part of this specification, in which—

The figure represents a perspective view of the entire machine.

Our invention consists, first, in the application of the power of steam to the working of a piston and plunger for pressing glass in molds, as will be explained.

It consists, second, in separating the piston-rod of the steam-cylinder from the piston-rod of the plunger in such a way as that while both shall descend together the steam piston-rod may rise without the other.

It consists, third, in the combination of an overpoise weight or its equivalent with the divided pistons and the pressing mechanism, so that when the press is run down by the action of the steam the operator may hold it down, while the steam-piston may rise up without it, and the overpoise, when released, raise it up.

It consists, fourth, in combining with the divided joint of the two pistons spring-jaws or their equivalents, that hold and release the mechanism by which the steam-valves are operated, thus making the press partially automatic and partially dependent upon the will or action of the operator.

To enable others skilled in the art to make and use our invention, we will proceed to describe the same with reference to the drawing.

A represents a bed-plate, which, for the sake of convenience of transportation, may be mounted on wheels B, as is usual with glass-presses. Upon this bed A is mounted the press and engine-frame C, sustaining at or near its top a vertical steam-cylinder, D, furnished with a valve or valves at E and steam ports and passages in the usual well-known way. F is a piston-rod working in the steam-cylinder D, its lower end coming in contact

with the piston-rod G, that operates the plunger in the mold. The lower part of this press may be like those in common use for pressing glass, and, as it constitutes no part of our invention, will not be further referred to. Where the two piston-rods F G meet, there are arranged two spring-jaws, a a, that are pivoted at b, and their rear ends, c c, are beveled off to form a seat for a wedge-piece, d, that is attached to a vertical rod, e, that may rise and fall through suitable guides, f. The lower end of the piston-rod F and the upper end of the rod G are beveled off, as shown in the drawing, and the jaws a a are so beveled as to fit in between the sloped-off ends of the two rods. To the upper end of the rod e is fastened a cord or chain, g, which passes around an arm, h, and thence over a friction-pulley that may be placed at i, though not shown, and at its end is fastened a weight, j. The arm h is connected to the valve in the valve-box E, and the drawing down of the rod e operates the valve in one direction, while its ascent when released by the falling of the overpoise-weight j operates said arm and valve in an opposite direction. The cord or chain g may be fastened to the arm h, or two or three turns of it made around said arm, so that the friction will be sufficient to move the valve-arm and consequently the valve.

H is a lever, pivoted to the main frame at k, and passing through the piston rod G, which lever, when released, will, by its weight I, at one end, raise up the pressing mechanism after the piston-rod F has been raised up by the steam in the cylinder D.

J is a screw-sleeve for raising or lowering the rod G to adjust it to the molds.

Steam may be admitted to the valve chest E in the direction of the arrow 1, and the exit-port may be in the direction of the arrow 2; and when the machine is of a portable character the steam-pipes should be flexible to admit of its being moved.

The operation is as follows: Suppose the steam piston to have been raised up and that the weight I to have raised up the pressing mechanism connected to the rod G. The mold and glass being now ready and properly placed the operator draws down the rod e, its wedge-piece d entering between the pieces c c of the jaws a a, which closes the jaws, the

steam, by the drawing down of the rod *d*, is admitted above the piston in the steam cylinder, and its rod *F* moves down and comes against the jaws *a*, which in turn rest upon the top of the plunger rod *G*, and thus the plunger-rod and plunger are driven down into the mold. Now, the ends of the two rods *F* *G*, as well as the sides of the jaws *a* *a*, being beveled off or angular, the continued pressure of the piston rod *F* will spread the jaws *a*, and in so doing bring those *c* against the wedge-piece *d*, forcing up said wedge-piece and the chain and weight then raise up the arm *h* and shut off or reverse the steam, so that the piston-rod *F* may rise. But before the steam is reversed the operator seizes hold of the lever *H* and holds the pressing apparatus for a few moments for the glass in the mold to chill or set after the piston-rod *F* has ascended or moved up. Then, by letting go the lever *H*, the overpoise *I* carries up the pressing apparatus and everything is ready for a second similar operation. The requisite pressure upon the glass is defined by the opening of the jaws *a*, which in turn shut off or reverse the steam, as described.

Having thus fully described our invention,

what we claim as new, and desire to secure by Letters Patent, is—

1. Operating the piston of a plunger in glass-pressing by the application of steam applied in the line of the piston or plunger, substantially as described.

2. The separation between the plunger-rod and the piston-rod, so that the latter may, after forcing down the plunger, raise up, while the plunger remains momentarily down, for the purpose and substantially in the manner described.

3. The combination of the overpoise-lever *H* with the pressing mechanism, for carrying up said mechanism after the piston-rod has ascended, substantially as described.

4. In combination with the piston and plunger rods, the spring-jaw levers *a* *e* and rod *e*, with its attachment to the arm *h*, for the purpose of working the valves of the steam-cylinder, substantially as described.
